UNITED STATES PATENT OFFICE.

HARRIS MORGAN WHITCOMB, OF ALBANY, WISCONSIN.

ATTACHMENT FOR LATHES.

Application filed August 24, 1925. Serial No. 52,082.

The primary object of this invention is to produce in a rapid, efficient and economical manner a leakproof sectional piston ring so formed as to hold its true circular form at all degrees of expansion and contraction, regardless of temperature, and which is adapted for application to variously sized cylinders without trimming or fitting or the exercise of even ordinary mechanical skill.

10 The invention further comprehends a novel method of manufacture carried out by simple and inexpensive apparatus capable of application to an ordinary engine lathe.

The foregoing and many other features of 15 novelty which characterize my invention are pointed out with particularity in the claims, annexed to, and forming a part of this specification. For a better understanding of the invention, however, and of the advantages 20 which it possesses reference should be had to the accompanying drawings wherein the now preferred form of ring together with the method and apparatus for making are illustrated.

25 In the drawings,

Figure 1 is a perspective view of a portion of a lathe illustrating the apparatus used in carrying out the first step of my method;

30 Fig. 2 is a longitudinal sectional view through the parts shown in Fig. 1;

Fig. 3 is an enlarged vertical sectional view illustrating the action of the yielding work engaging plate and showing the relation of the bits to the work at the completion 35 of the operation wherein the ring is made eccentric;

Fig. 4 is a detail of the bit carrier and set screw;

40 Fig. 5 is a view similar to Fig. 1 but illustrating the form of tool plate apparatus used in the ring flanging and thickness reducing step of the process;

Fig. 6 is a longitudinal sectional view through the parts shown in Fig. 5;

45 Fig. 7 is an enlarged vertical sectional view similar to Fig. 3 but showing the relation of the apparatus of Fig. 5 to the work at the start of the flanging step;

50 Fig. 8 is a view similar to Fig. 7 but showing the parts upon completion of the flanging step;

Fig. 9 is a fragmentary detail in plan showing the construction whereby the bit and roller carriers are made adjustable;

55 Fig. 10 is a plan view of a ring-like piece

of metal stock from which the ring may be formed;

Fig. 11 shows a ring section after the first step of the method wherein it is reduced to eccentric form;

60 Fig. 12 illustrates the flanged and width reduced ring section produced by the second major step of the process;

Fig. 13 is a group perspective view depicting two ring sections ready to be assembled, 65 and

Fig. 14 shows the assembled piston ring.

Referring specifically to the drawings, wherein like reference characters designate like parts throughout, numeral 1 denotes the 70 body portion of an ordinary lathe which is preferably (although not necessarily) of the type having an automatic stop and carriage feed. 2 indicates the lathe spindle and 3 the carriage, the latter having a conventional 75 compound rest 4 for the tool post 5. No novelty is being claimed for the lathe, and accordingly further description thereof is unnecessary.

In carrying out my process I employ a 80 chuck 6 having a circular work-receiving recess 7 in one face, and a second recess 8 in its opposite face to receive the projecting end portion of the chuck holder 9 whose shaft 9^a is clamped in the tool post 5. Bolts 85 9^c carried by the circumferential flange 9^b of the carrier serve to detachably mount the chuck in place. Different sized chucks 6 will, of course, be used for different sized work.

90 The material preferably used in making up the sections of my ring is ordinary piston rings although other ring stock may be transversely split and used to advantage. As shown in Fig. 1 the transversely split ring section 10, whose normal diameter is a shade larger than the work receiving recess 7, is sprung into the latter to be held against rotation by a chuck carried key 6^a which engages between the walls of the split 10^a.

100 The spindle carried tool appliance for first operating upon the ring stock to make it eccentric comprises an annular tool plate 11 appropriately fastened to its shaft or arbor 12 at one end thereof. Rods 13 freely slideable in transverse holes in the plate 11 carry at their outer ends a disk 14. By means of helical springs 15, surrounding the rods 13 and interposed between the plate and the disk 14, the latter is brought to bear against the 110

ring stock 10 to prevent its displacement while being worked upon by the bits 19 which are designed to project through radial slots 14^a in the disk. Cotter pins or other stops 16 passing through selected holes 17 in the rods 13 engage the back of plate 11 to limit the action of the springs to advance the disk 14.

The holders 18 carrying the bits 19 have 10 their shanks 20 slidable in radial slots 21 of the plate 11. Thus variously sized work may be operated upon,—nuts 22 on the threaded ends of the shanks serving to lock the holders in a "set" position. The shanks 20 of the 15 holders 18 are square as shown in Fig. 4 and consequently cannot turn in the slots 21. Set screws 23 which may be suitably graduated extend from the periphery of the plate 11 into each of the slots 21 to engage the holders 18. 20 Accurate adjustment of the latter may be quickly attained.

The ring having been positioned in the chuck, the carriage 3 is moved forward until the ring engages and compresses the disk 14 25 to project the bits 19 through the disk slots 14^a. Adjustment of the compound rest or tool post mounting is now (or may have previously been) made to position the ring 10 eccentrically with respect to the axis of the 30 tool plate 11. The bits 19 now bear only upon the inner wall of the half of the ring adjacent the split 10^a. The adjustment of the rest is, of course, transversely of the carriage 3. The operation of the lathe, that is, 35 the rotation of the sprindle 2 and progressive feeding of the carriage theretoward, results in the formation of an eccentric ring section whose wall at the split 10^a is one-half its original width.

40 The next operation consists in reducing to one-half thickness the half of the ring in proximity to the joint 10^a and in the same operation forming a crescent-like flange and shoulder upon the other half of the ring. 45 The boring apparatus used is shown in Figs. 4 and 5 and consists of a spindle carried tool plate 24, similar in all respects to the tool plate 11 except that the yielding work-engaging disk 14 is absent. In lieu thereof a 50 plurality of spring pressed rollers 25 are employed. Each of these rollers is journaled on the end of a stem 26 slidingly working in a sleeve-like carrier 27. The carriers 27 are 55 adjustably mounted in radial slots 24^a intermediate the slots 31 of the plate 24 which carry the bit holders 18. Nuts 27^a on the reduced and end-threaded portions of the carriers 27 serve to draw shoulders 27^b against the outer face of the tool plate 24 to lock the 60 carriers in a "set" position. The rollers 25 are now aligned to engage the outer portion of the edge of the eccentric ring 10 in the chuck 6. The carriers 27 have their outer ends cored out to define a chamber 27^c to 65 house a coil spring 28 which bears against

the roller carrying bearing for urging the stem 26 outwardly. A stop 26^a on the inner end of each stem 26 engages the back of the plate 24 to limit outward movement of the stem and roller 25.

Figs. 7 and 8, respectively, clearly illustrate the relation of the bits 19 and rollers 25 to the work at the commencement and upon the completion of the work flanging and width reducing step of the process. The bits 19 and rollers 25 are adjusted so as to bear against the projecting face of the ring 10 in a true circle. When the lathe is operated the rollers act to hold the ring 10 in place in the chuck while the bits reduce the same to one-half the thickness of the ring throughout approximately the quarter of its circumference which is on both sides of the split 10^a. Inasmuch as the ring is positioned eccentrically with respect to the path of travel of the bits there will be left upon the half of the circumference opposite the split a crescent-like flange 10^b and shoulder 10^c, the depth of which flange will be equal to the original thickness of the ring. The width of the shoulder 10^c will, of course, correspond exactly to the width of that portion of the ring which is reduced in thickness by this operation. Thus two ring sections may be fitted together with the split 10^a of the one ring being disposed behind the shoulder 10^c of the other ring. Figs. 12, 13 and 14 clearly illustrate the formation of the ring sections and the manner in which they are adapted to fit together. For instance, Fig. 14 shows the assembled ring of true concentric shape formed of the two eccentric ring sections 10. It will be understood and appreciated by those skilled in the art that my ring may be repeatedly stretched over a piston without distortion and will in fact expand and contract beyond all requirements and at the same time retain its true circular form at all diameters.

Further, the ring can be machined fully contracted or expanded with equal facility. A 105 ring of this character includes no joints or openings for the downward passage of gas which pollutes the oil and causes excessive wear on the motor bearings and it has an equal wearing surface throughout its circumference. Further carbon never collects under these rings as with common one piece rings. With the use of my ring the necessity of hammering, re-turning, rolling, or the like, is obviated and no mechanical skill whatever 110 is necessary to fit the ring in a piston for a given sized cylinder. The range of size of pistons and cylinders to which the ring may be applied is limited only by the size of the joint 10^a and the width of the space 115 between the piston and the cylinder wall. By cutting out a section of considerable size at this point the ring will be free to expand or contract to fit pistons of widely different diameters. There is a further feature of the 120

invention which is worthy of notice and that is that there is no friction between the two ring sections as neither section crowds the other in an outward direction while expanding. The wear between the parts is thus reduced to a minimum and my ring will expand as readily as an ordinary single piston ring.

In conclusion it is to be noted that the initial crosswise adjustment of the carriage 10 to position the ring eccentrically of the lathe spindle suffices for the operation wherein the ring is rendered eccentric and also for the operation wherein its thickness is reduced 15 and the crescent-like flange 10° and shoulder 10° are formed. In this second operation the rollers 25 and bits 19 are merely adjusted to proper position. Considerable advantage resides in having the chuck stationary which obviates the necessity of stopping the spindle 20 when a ring is to be removed.

Having thus described the invention, what is claimed is:

1. A cutting attachment for lathes or the like comprising a tool plate having means for attachment in a chuck, said tool plate having a plurality of radially arranged transverse slots, cutting elements working in certain of said slots and having means whereby they may be adjusted and locked in a set position, 30 shanks extended through other of said tool plate slots and radially adjustable therein, each of said shanks having a socket in its outer end, an antifriction work-engaging roller and bearing therefor axially slideable in 35 said socket, a spring interposed between said bearing and the inner end of said socket for yieldingly projecting said roller in the direction of the work, and means for holding said bearing and shank in assembled relation and 40 positionable to variably limit the relative axial movement of said bearing in said socket.

2. A cutting attachment for lathes or the like comprising a tool plate having means for attachment in a chuck, said tool plate having a plurality of radially arranged transverse slots, cutting elements working in certain of said slots and having means whereby they may be adjusted and locked in a set position, 45 shanks extended through others of said tool plate slots and radially adjustable therein, each of said shanks having a socket in its outer end, an antifriction work-engaging roller and bearing therefor axially slideable in 50 said socket, a spring interposed between said bearing and the inner end of said socket for yieldingly projecting said roller in the direction of the work, and means for holding 55 said bearing and shank in assembled relation and positionable to variably limit the relative 60 axial movement of said bearing in said socket, said aforementioned holding means comprising a stem carrying said bearing and extending through said shank and a stop engageable with said stem at different points.

3. An attachment for lathes and the like

comprising a tool plate having means for attachment to a lathe spindle to be rotated therewith, an instrumentality carried by said tool plate for holding the work in a chuck comprising a longitudinally bored carrier 70 having a socket in one end, a stem extending through said bore, an anti-friction element, a bearing therefor carried by one end of said stem and designed to be received in said socket, and yielding means housed in said socket 75 and engaging said bearing for urging the anti-friction element in the direction of the work.

4. In an attachment for lathes and the like including a tool plate, the combination of an 80 instrumentality for holding the work in a chuck comprising a longitudinally bored carrier having a socket in one end, the other end of said carrier being threaded for the application of a nut and the intermediate exterior 85 portion of said carrier being shouldered whereby said carrier may be adjustably clamped in a slot of said plate, a stem extending through said bore, an anti-friction element, a bearing therefor carried by one end 90 of said stem and designed to be received in said socket, and yielding means housed in said socket and engaging said bearing for urging the anti-friction element in the direction 95 of the work.

5. A cutting attachment for lathes or the like comprising a tool plate having means for attachment in a chuck, said tool plate having a plurality of radially arranged transverse slots, cutting elements working in certain of said slots and having means whereby they may be adjusted and locked in a set position, 100 shanks extended through other of said tool plate slots and radially adjustable therein, and axially disposed work engaging elements 105 adjustably carried by said shanks for movement toward the work.

6. A cutting attachment for lathes or the like comprising a tool plate having means for attachment in a chuck, said tool plate having a plurality of radially arranged transverse slots, cutting elements working in certain of said slots and having means whereby they may be adjusted and locked in a set position, 110 shanks extended through other of said tool plate slots and radially adjustable therein, each of said shanks having a longitudinal bore therein and socket at one end thereof communicating with said bore, a rod slideable 115 in said bore and having a work engaging head receivable in said socket, and a spring in said socket engaging said head for urging the same toward the work.

7. A cutting attachment for lathes or the like comprising a tool plate having means for attachment in a chuck, said tool plate having a plurality of radially arranged transverse slots, cutting elements working in certain of said slots and having means whereby they may be adjusted and locked in a set position, 125

- shanks extended through other of said tool plate slots and radially adjustable therein, each of said shanks having longitudinal bore therein and a socket at one end thereof communicating with said bore, a rod slidable in said bore and having a work engaging head receivable in said socket, a spring in said socket engaging said head for urging the same toward the work, and a variably positionable stop at the other end of each rod and engaging the end of said shank to limit movement of said head toward the work under influence of said spring.
8. An attachment for lathes and the like comprising a tool plate having means for attachment to a lathe spindle, an instrumentality carried by said tool plate for holding the work in a chuck comprising a longitudinally bored carrier, means securing the carrier to one face of the plate for lateral adjustment thereon, a stem extending through said carrier bore, an anti-friction element, a bearing

therefor carried by one end of said stem, and yielding means for urging the anti-friction element in the direction of the work.

9. An attachment for lathes and the like comprising a tool plate having means for attachment to a lathe spindle to be rotated therewith, an instrumentality for holding the work in a chuck comprising a longitudinally bored carrier, a stem extending through said carrier bore, an anti-friction element, a bearing therefor carried by one end of said stem, and yielding means acting on said stem for urging the anti-friction element in the direction of the work.

10. The combination set forth in claim 9 and said stem being rotatable in said carrier bore whereby the anti-friction element will be enabled to follow the work in the rotation of the tool plate.

In testimony whereof I affix my signature.

HARRIS MORGAN WHITCOMB.
